UNITED STATES PATENT OFFICE.

EDWARD HUBER AND JACOB W. MILLER, OF MARION, OHIO.

PNEUMATIC STRAW-STACKER.

SPECIFICATION forming part of Letters Patent No. 555,902, dated March 3, 1896.

Application filed June 26, 1895. Serial No. 554,104. (No model.)

To all whom it may concern:

Be it known that we, EDWARD HUBER and JACOB W. MILLER, of Marion, in the county of Marion and State of Ohio, have invented 5 certain new and useful Improvements in Pneumatic Straw-Stackers; and we do hereby declare the following to be a full, clear, and exact description of the invention, such as will enable others skilled in the art to which 10 it appertains to make and use the same.

Our invention relates to an improvement in pneumatic stackers for thrashing-machines, and more particularly to devices for supporting the stacker-trunk in its operative position 15 and permitting it to be properly folded over the top of the machine when not in use, the object of the invention being to so construct and arrange the devices for raising or straightening out the stacker-trunk that when the latter is folded on or over the top of the machine 20 said devices can be so disposed as not to project upwardly above the stacker-trunk, whereby the machine will be permitted to pass through barn-doors if desired.

25 A further object is to provide a pneumatic stacker made in sections hinged together, with simple and efficient means for straightening the same to dispose the parts in position for use.

30 A further object is to provide a pneumatic stacker-trunk made in sections hinged together, with means for preventing the upper or forward part of the trunk from falling farther down on the top of the thrashing-machine 35 than is desired.

With these objects in view the invention consists in certain novel features of construction and combinations and arrangements of parts, as hereinafter set forth, and pointed out 40 in the claim.

In the accompanying drawings, Figure 1 is a side elevation of a portion of the framework of a thrashing-machine, showing my improved stacker in position for use. Fig 2 is 45 a view showing the stacker-trunk folded over the top of the machine.

A represents a portion of a thrashing-machine, to the rear end of which the straw-stackers is applied. The stacker-trunk, which 50 is made in two parts B B', is carried by a base B², revolubly mounted on the rear of the machine in any approved manner.

The parts B B' of the trunk are hinged together by means of a hinge a, attached to the under or rear edges of the parts of the trunk 55 at their abutting ends, so as to permit the trunk to be readily folded or "broken" over the top of the machine. In order to prevent the forward portion B of the trunk from falling too far down on the top of the machine, 60 the two parts of the trunk are connected together by means of a link or stay D, preferably having an elongated slot b, one end of said link or stay being attached to the part B of the trunk and the other end adapted to 65 engage a hook c on the part B' of said trunk, which hook enters the elongated slot in the link or stay. From this arrangement it will be seen that when the stacker is folded over the machine the trunk will break at the hinge 70 between the parts B B' and that the downward movement of the forward part B of the trunk will be limited by the link or stay D. When the stacker is straightened out or distended for use, the hook c will move freely 75 through the elongated slot in the link or stay.

A bracket d is mounted on the base B² at each side of the part B' of the trunk, and to the upper ends of said brackets a standard 1 is pivotally connected. A prop or standard 80 2 is also pivotally connected to the inner end of the part B of the trunk. A truss rod or cable 3 is connected at one end to the upper end of the standard 1, passed through a guide 4 at the upper end of the prop or standard 2, 85 and at its other end is attached to the forward end of the part B of the trunk. Bearings 5 are carried by the base B² for a shaft 6 of a drum 7. One end of the shaft 6 is provided with a worm-wheel 8, which receives 90 motion from a worm-shaft 9, and the latter is provided with a wheel 10, by which to operate it. One end of a rope 11 is wound on the drum 7, passed over pulleys 12 13, attached to the base B² and standard 1, respectively, 95 and at the other end said rope is attached to said base B². When the standards 1 2 are in their normal positions and the windlass, constructed as above explained, is operated, the forward portion B of the trunk will be raised 100 and brought into alignment with the portion B' of said trunk.

When the trunk of the stacker is folded over the top of the machine, as shown in Fig.

2, the standards 1 2 can be turned down, so as not to be in the way when it is desired to run the machine through a barn-door, and the truss rod or cable 3 can, if desired, be removed.

5 Our improvements are simple in construction, easy of application, and effectual in the performance of their functions.

Having fully described our invention, what 10 we claim as new, and desire to secure by Letters Patent, is—

In a stacker, the combination with a trunk made in two sections hinged together at their lower sides, of a slotted link hinged to the

upper side of one section, a hook on the other 15 section projecting into the slot in the link whereby to limit and define the extent of depression of the outer section of the trunk, and means for raising and lowering the said section of the trunk, substantially as set forth. 20

In testimony whereof we have signed this specification in the presence of two subscribing witnesses.

EDWARD HUBER.
JACOB W. MILLER.
